UNITED STATES PATENT OFFICE.

OSKAR ZAHN, OF BERLIN, GERMANY.

MUFFLE-FURNACE FOR ENAMELING.

1,124,380.

Specification of Letters Patent. Patented Jan. 12, 1915.

Application filed September 16, 1913. Serial No. 720,022.

To all whom it may concern:

Be it known that I, OSKAR ZAHN, subject of the Emperor of Austria-Hungary, residing at 10 Darmstädterstrasse, Berlin, in the German Empire, have invented certain new and useful Improvements in Muffle-Furnaces for Enameling, of which the following is a specification.

This invention relates to muffle furnaces for firing enameled or other ware without direct flame contact and has for its object to improve the construction of such furnaces.

Hitherto it has been usual to place the articles to be fired or enameled upon a grate within the muffle so that the articles are subjected to the heat radiating from the sides, bottom and comparatively thin top or cover of the muffle. As the cover of the muffle is heated by the surrounding gases, the upper part of the muffle chamber becomes extremely highly heated and the temperature thereof is still further increased by the heat radiating from the bottom and sides of the muffle. In consequence thereof, the upper part of the articles within the muffle are subjected to greater heat than the lower parts so that the articles are frequently over-fired at their upper part whereas the lower part thereof is incompletely fired. Moreover the output of the furnace is small, especially when the articles are to be well fired as this requires great care.

According to the present invention the foregoing disadvantages are obviated by preventing excessive heating in the upper part of the muffle chamber. This object may be attained in various ways. For example, the muffle furnace may be so constructed that the cover of the muffle is not subjected to the heat of the furnace gases, or the cover of the muffle may be wholly or partly insulated or of such thickness that the heat will not readily pass therethrough, or the cover of the muffle may be subjected to the heat of the gases only periodically. It may also be found necessary, when enameling certain goods, that the cover of the muffle be not only protected from the heat of the gases but also cooled so as to lower the temperature within the muffle. It will be readily understood that when the cover of the muffle is not heated or is insulated from the heat, or of greater thickness, or if the cover is cooled, the latter will absorb heat from the interior of the muffle instead of radiating

heat as heretofore usual. Moreover the muffle may be so constructed that a part thereof, such as the cover, is heated to different degrees of temperature. If, for example, the front part of the cover is heated, no dangerous effect will arise therefrom owing to the cooling action through the door at the front of the furnace, whereas at the rear of the furnace, where no cooling action takes place, it would be disadvantageous to heat the cover of the muffle. This may be readily attained, for example, by providing the rear part of the muffle with no cover, carrying it up to the roof or arch of the furnace chamber, while providing the muffle with a cover at its forward part, the gases being allowed to pass over this cover either wholly or in part or from time to time as required.

If desired, the cover of the muffle may be partly heated, for example at the side edges, while the upper part or crown of the cover is protected from the external heat. This method may be employed in cases where the protection of the whole cover from heat would, owing to the thickness of the cover, result in too low a temperature within the muffle.

In order that the invention may be more clearly understood, reference is made to the accompanying drawings showing by way of example various embodiments of my invention.

Figures 1 to 5 illustrate one type of the improved muffle furnace in which the furnace arch constitutes the cover of the muffle chamber, the figures showing various embodiments of this type, in transverse section. Fig. 6 is a longitudinal section through a slightly modified type of muffle furnace in which the furnace arch only constitutes the cover of the rear part of the muffle chamber. Fig. 7 is a transverse section through a further modified type of muffle furnace in which the cover of the muffle chamber is covered by means of insulating material. Fig. 8 is a view similar to Fig. 7 showing a further modification in which the cover of the muffle chamber is of greater thickness. Fig. 9 illustrates a further modification in which the cover is protected by movable protecting plates. Fig. 10 illustrates a further modification in which only the crown of the muffle cover is protected. Fig. 11 illustrates a further type of muffle chamber provided with an upper

cooling space, and Fig. 12 illustrates a slight modification of the furnace illustrated in Fig. 11.

Referring firstly to Fig. 1 of the drawings: The articles to be fired or enameled are supported upon a grate *d* within the muffle chamber *a* which is formed by means of a bottom plate *c* and side walls *e* arranged within a furnace *b* to which hot gases are supplied through an opening or openings *b*¹ in the bottom thereof. The side walls *e* are carried up to the furnace arch *z* so that no heat is radiated from the top of the muffle chamber *a*, the articles to be fired or enameled receiving heat only from the side walls *e* and bottom *c*, while the heat rising in the chamber *a* is absorbed by the furnace arch *z*. In order to prevent any possibility of excessive heat in the upper part of the muffle chamber, owing to the heat being trapped or accumulating in the upper part of the side channels *x* in Fig. 1, the side walls may be either insulated or increased in thickness at their bottom parts so as to reduce the heat conducted thereby or, if desired, the walls *e* of the muffle chamber may be inclined outwardly and upwardly so as to attain the same effect.

Fig. 2 illustrates a modification in which the side walls *e* are thickened at their upper parts at *y* so as to reduce the heat conducted thereby at the upper part thereof. This arrangement has the further advantage that the side channels *x* are tapered toward their upper ends.

In the modification illustrated in Fig. 3 the upper parts of the side walls *e* are protected by means of masonry *w* beneath the furnace arch *z*.

In the constructions illustrated in Figs. 4 and 5 the side walls *e* are inclined outwardly, the side walls *e* in Fig. 4 coinciding at their upper ends with the points from which the arch *z* springs, so that the side channels *x* are correspondingly tapered upwardly resulting in a gradual diminution in the heat transmitted to the interior of the muffle chamber from the bottom upwardly. In Fig. 5 the side walls *e* are still further outwardly inclined so that their upper ends are at a lower level than the springing points of the arch *z*, thus still further lowering the highest point from which heat is radiated.

Fig. 6 illustrates a slight modification of the furnace illustrated in Figs. 1 to 5 in which the furnace arch *z* instead of forming the cover for the whole of the muffle chamber *a* forms only the cover of the rear part of the muffle chamber while the front part of the muffle chamber is provided with a cover *h* forming a passage *b*² over the front part of the muffle chamber *a*, the passage *b*² being formed between front furnace arches *z*¹ and *z*² and the cover *h* and the rear fur-

nace arch *z*. It will be noted that in this case no dangerous effect will arise from heating the cover *h* owing to the cooling action through the door (not shown) at the front of the furnace. It will of course be understood that if desired, the gases may be allowed to pass over the cover *h* through the passage *b*² either wholly or in part or from time to time as required.

Instead of dispensing with the muffle cover as in Figs. 1 to 5, the muffle cover *i* may be insulated by means of insulating material *f* as illustrated in Fig. 7 so that little or no heat passes through the cover *i* to the interior of the chamber *a*. If desired, however, the cover *i*, instead of being insulated as in Fig. 7, may be correspondingly increased in thickness as illustrated in Fig. 8 and if required other parts of the muffle may be increased in thickness so as to reduce the amount of heat penetrating the muffle to the interior upper part thereof. For this purpose the side walls *e* in Fig. 8 are shown enlarged at their upper ends at *e*¹, at the same time serving as a better support for the heavy cover *i*.

As illustrated in Fig. 9 the cover *i* may, if desired, be provided with movable protecting plates *k* operated by means of rods *l* passing through to the outside of the furnace and terminating in a suitable handle *m*, so that the heat conducted by the cover *i* may be regulated according to requirements. It will be understood that in this manner the cover may be heated to different degrees of temperature.

Fig. 10 illustrates a further modification in which the cover *i* is heated at its side edges while the upper part or crown thereof is protected by means of insulating material *n* from the external heat, the insulating material *n* being inclosed in vertical walls *o* forming gas passages *p* above the side edges of the cover *i*.

It is in many cases desirable, when enameled, to cool the upper part of the muffle chamber as, for example, in the case of very high articles which almost touch the cover of the muffle chamber, and in this case, as illustrated in Fig. 11, a cooling chamber *g* may be provided above the cover *i*, this cooling chamber being separated from the furnace *x* by means of horizontal partitions *q*. It is however, in many cases desirable to provide for the passage of the flames over the cover *i* of the muffle chamber from time to time and this may be effected as illustrated in Fig. 12 by providing movable partitions *r* separating the cooling chamber *g* from the side passages *x*. The movable partitions *r* may be operated by means of rods *s* passing through the furnace walls and terminating in suitable handles *t*. The furnace gases may pass away, when the partitions *r* are in their closed position, through

flues *u* provided with regulating valves *v* indicated in dotted lines in Fig. 12.

The hereinbefore described muffle furnaces constructed according to the present invention are excellently suitable for enameling work, no particular care being required on the part of the workman while the consumption of fuel is comparatively small. The loss due to faulty firing is also considerably reduced. The special construction of the furnaces also results in longer life thereof. More especially is this the case with the furnaces constructed according to Figs. 1 to 5 as the side walls *e* do not require to withstand the weight of the muffle cover.

I claim:—

1. In combination, a furnace chamber to which heating gases are supplied and an inclosed muffle so situated within said chamber that the gases can pass up at the sides of said muffle but not over the top thereof.

2. In combination, a furnace chamber to which heating gases are supplied, and an inclosed muffle, the top of said chamber forming the top of said muffle.

3. In combination, a furnace chamber to which heating gases are supplied and an inclosed muffle therein whose sides extend up to the top of said chamber.

4. A muffle furnace comprising a furnace chamber, and a muffle in said chamber, the sides of said muffle reaching to the top of said chamber and forming side gas channels adapted to heat the upper part of said muffle to a lesser degree than the lower part.

5. A muffle furnace comprising a furnace chamber and a muffle in said chamber, the sides of said muffle reaching to the top of

said chamber and having their outer faces 40 inclined outwardly and upwardly.

6. A muffle furnace comprising a furnace chamber and a muffle in said chamber, the sides of said muffle reaching to the top of said chamber and being inclined outwardly 45 and upwardly and of equal thickness throughout.

7. A muffle furnace comprising a furnace chamber, a muffle in said chamber, the sides 50 of said muffle reaching to the top of said chamber, and means for diminishing the conduction of heat at the upper ends of said sides.

8. A muffle furnace comprising a furnace chamber, a muffle in said chamber, the sides 55 of said muffle reaching to the top of said chamber, and means for protecting the upper ends of said sides from the furnace gases.

9. A muffle chamber comprising a furnace 60 chamber, and a muffle whose sides are inclined outwardly and bear at their upper ends against the sides of said furnace chamber.

10. A muffle furnace comprising a furnace chamber, a muffle in said chamber, the front part of the sides of said muffle reaching to the top of said chamber, and a cover over the rear part of said sides leaving a gas passage between said cover and the top 70 of the furnace chamber.

In testimony whereof I have affixed my signature in presence of two witnesses.

OSKAR ZAHN.
